M. M. Patent

An Schedule referred to in these Letters Patent and making part of the claims containing a description in the words of the said Schedule of McKinney himself of his Improvement in the application of the power of the Pendulum to a Machine called a Swinging Cradle.

To all to whom these presents shall come. Be it known that I, John McKinney of Chester in the County of Butler and State of Ohio have invented a new and useful improvement in the application of the power of the Pendulum Clocks to a Machine called a Swinging Cradle, and that the following is a full and exact description of the construction and operation of the said Machine as invented by me. A is the cradle swinging as a Pendulum, weight b, b are the pendulum wires of parting by which the cradle is suspended, c c are pivot hooks in the middle of which the pendulum wires are attached by loops on the ends of the wires d, platform on which the boy is set that operates the wheel e, by continuing the axle of the platform converges with cranks at each end by which the power is applied, f f cords from the barrel of the main wheel to which the weights are attached passing over pulleys to the centre posts above which the weights pass thro' a cavity of 8 inches diameter h, h, centre posts 6 inches diameter with a cavity of 8 inches diameter down which the weights pass i, cranks running lengthwise to support a table.

This piece of furniture (the Swinging Cradle) may be made in various forms to suit the fancy of inventors. The form here presented is that of a fancy bedstead—the height of four feet—the length two feet eight inches the width one foot eight inches supported by four pieces framed into the posts, having in front an Arch, back for convenience and good appearance. The posts consist of three wheels, the main wheel is cast iron 6 inches diameter containing 16 cogs with a barrel, & the axle 8 inches diameter on which the weight hangs are mounted. The axle of the wheel projects so as to receive a crank by which as it is wound an eight day clock the barrel being fixed on the axle in the same

1484.

Manner as that of the clock. The Counter wheel is 17 inches diameter (of Cast iron) containing 48 cogs with a pinion on the axle containing 20 cogs which receive the cogs of the main wheel. The main wheel is of 3 inches diameter with 24 teeth, also having a pinion on its axle containing 6 cogs which receive the cogs of the counter wheel. The axles of the wheels are 2 1/2 inches in length from shoulder to shoulder and of sufficient strength to receive the power. The axle to which the pallet or牙 is attached should be of Cast steel 3/4 inches long and 1/2 inch diameter, in the ends of this axle are the branks which fly on the wires by which the counter is suspended. The weight attached to each cord is 10 pounds. The whole machine is on the principle of the pendulum clock with this difference only that it is composed of three wheels instead of a greater number.

The pallet or牙 of a suitable size to escape from getting at any vibration. What I claim as new and as my own invention a discovery in the above described machine and for the use of which I ask an exclusive privilege is the application of the power of the pendulum clock to that purpose.
